MULTICOLOR PENCIL WITH EXCHANGEABLE LEADS

Willy Schmieglitz, Berlin, Germany

Application September 15, 1939, Serial No. 295,066
In Germany September 14, 1938

5 Claims. (Cl. 120—14)

This invention relates to a multicolor pencil with exchangeable leads.

Multicolor pencils of this type are already known. They are generally constructed so that every one of the colored leads to be actuated singly is shiftable in the longitudinal direction by means of an actuating element projecting from the casing in lateral direction. These known multicolor pencils are open to the objection that a separate actuating element is necessary for each lead and that these actuating elements slightly project from the pencil casing, this being especially undesirable if the actuating elements are not absolutely smooth but, for instance, beaded or serrated to facilitate handling of the same because thereby the diameter of the multicolor pencil is slightly enlarged.

These inconveniences of the known multicolor pencils are avoided according to the invention in that the leads are no longer pushed but pressed, by this is meant that the longitudinal shifting of the leads is produced by depressing once or several times a press pin or press sleeve in the rear end of the casing. Magazine pencils to be actuated by pressure are known, but it is believed to be new to use a press sleeve for multicolor pencils, the particular construction which becomes necessary therefore being also new.

Two embodiments of the invention are illustrated by way of example in the accompanying drawing, in which

Fig. 1 shows a multicolor pencil in elevation, Fig. 2 shows this multicolor pencil in longitudinal section,

Fig. 3 shows in longitudinal section the stationary and shiftable tube,

Fig. 4 is a top plan view of Fig. 3,

Fig. 5 shows the press sleeve in elevation,

Fig. 6 shows the rod with grooves,

Fig. 7 is a cross-section on line VII—VII of Fig. 6,

Fig. 8 is a cross-section on line VIII—VIII of Fig. 6,

Fig. 9 is a cross-section on line IX—IX of Fig. 6,

Fig. 10 shows one of the resilient lead holders mounted in the grooves of the rod shown in Fig. 6,

Fig. 11 shows in elevation the internal parts of the multicolor pencil according to a second form of construction,

Fig. 12 shows in longitudinal section the stationary tube shown in Fig. 11, and

Fig. 13 shows in longitudinal section the shiftable tube also shown in Fig. 11.

The multicolor pencil according to the first form of construction consists of a casing 1, a point 2 screwed on the front end of the casing and an insertable abutment piece 3 at the rear end of the casing and in which abutment piece 3 a press-sleeve 4 is provided. In the casing 1 a resilient element 5 is arranged which consists of a tube 6 and of a tube 7 connected the one with the other by two blade springs 8 and 9 so that tube 6 can be shifted relative to tube 7. The upper blade spring 8 is fixed on tube 7 by means of a rivet 10 and has a slot 11 (Fig. 4), and the blade spring 9 is connected with tube 6 by a rivet 12 and has a slot 13. Both of these oblong holes are of similar length. The rivets 10 and 12 extending through the slots 11, 13 respectively limit the shifting movement of the tubes 6, 7. The front end of the blade springs 8 and 9 are downwardly curved towards the interior of tube 7 and destined to come into engagement with an element 20 of the lead holder which will be described hereinafter.

The tube 7 has a slot 14 extending from its front end which slot is slightly wider than the blade springs so that the curved end of these 25 blade springs project through this slot. A ring 15 is placed around tube 6 to serve as abutment for the abutment piece 3 to be inserted into the casing 1. This ring 15 is open in the upper side to accommodate the blade springs 8 and 9. The 30 tube 6 has near its rear end a projection 16 serving as stop for the press sleeve 4 which has a slit 17 in its front end corresponding to this projection 16. In this manner turning of the press sleeve 14 relative to the resilient element 5 is prevented, so that this element 5 must participate in any turning movement of the press sleeve 4. A spiral spring 20 is arranged between the two tubes 6 and 7 and has the tendency to maintain these tubes in their extreme separated 35 position. A rod 18 extends through the element 5 and has as many grooves 19 as there are colored leads, for instance, as shown, four such grooves. The portion of the grooved rod 18 which is guided in the resilient element 5 is of circular cross-section, as shown in Fig. 7, which is a section on line VII—VII of Fig. 6. The next following portion of the rod 18 is of square cross-section, as shown in Fig. 8, which is a section on line VIII—VIII of Fig. 6, and the front portion is again of 40 circular cross-section, as shown in Fig. 9, which is a cross-section on line IX—IX of Fig. 6.

A ring 21 is mounted at the middle of the length of the grooved rod 18 which extends up to this ring through the resilient element 5, said 45

ring serving as abutment for this resilient element. The grooved rod 18 has at its front end a collar sleeve 22, as shown in Figs. 2, 6 and 9. A resilient lead holder 23 (Fig. 10) is mounted in 5 each of the grooves 19 of rod 18. This lead holder consists of a wire having a holder 24 at one end and a portion 25 serrated like a saw blade at the other end. The resilient lead holders 23 are placed in the grooves of rod 18 so that 10 the tubular holders 24 project from the collar 22, the remaining portions 23 to 25 being located in the grooved rod 18. A nose 26 on the front end of the serrated portion 25 bears against the front side of ring 21. A spring 27 arranged 15 between collar 22 and noses 26 of the lead holders 23 serves to hold all the lead holders in the normal position shown in Fig. 2. The bent front ends of the two blade springs 8 and 9 engage in the serrated portion 25 of one of the lead holders at that portion of the grooved rod which is 20 of square cross-section.

In the normal position the elements are in the position shown in Fig. 2. If a colored lead has to be moved forward so that it projects from the 25 point 2 of the multicolor pencil, a pressure has to be exerted upon the press sleeve 4. As slit 17 of the press sleeve 4 is pushed over the projection 16 this press sleeve is connected with the resilient element 5 and the pressure is transmitted to 30 this element 5 and upon the grooved rod 18. The collar 22 bears, however, against a shoulder 28 formed by the end of point 2, so that shifting of the grooved rod 18 cannot take place. Consequently, the tube 6 is shifted to the left in 35 pressing the spring 20 located between the tubes 6 and 7, the lower blade spring 9 participating in the movement of this tube.

The pressing-in movement of sleeve 4 is limited by the abutment piece 3, and the movement 40 of tube 6 and of blade spring 9 fixed on the same is limited by the end of slot 13. As the blade springs 8 and 9 are coupled with the lead holder 23, through the serrated portion 25 of the same, the movement of the blade spring 9 to the left is 45 transmitted to the lead holder 23. This lead holder is therefore moved forward in the grooved rod 18 in compressing the spring 27, as the nose 26 bears against this spring. When the press sleeve 4 is released this press sleeve and the tube 6 with blade spring 9 are returned into their initial position by the action of spring 20. The blade spring 8, however, securely holds the lead holder 23 in the adjusted position. By repeated depressing of the press sleeve 4 the desired 55 colored lead can be moved to project from the point of the multicolor pencil owing to the said blade-like portion 25 of the lead holder 23, each time by the length of one tooth or of several teeth.

If the color lead has to be returned into its 60 initial position, the press sleeve 4 has to be turned in any direction. By the turning of the press sleeve 4, the resilient element 5 is drawn along so that the curved front ends of the blade springs 8 and 9 slip off the saw blade like portion 25 of 65 the lead holder 23, this being facilitated by the square cross-section of the grooved rod 18, and the spring 27 can then shift the lead holder 23 to the right until its nose 26 bears against ring 21. According to whether the press sleeve 4 is 70 turned back into its former position or into any other operative position, in accordance with marks on the outer side of the abutment piece 3, either the same or any other color lead will be actuated at the next following depression of the 75 press sleeve 4.

The form of construction shown in Figs. 11 to 13 differs from that which has just been described substantially in that the springs are not wound around the grooved rod but are freely located in the interior of the same and that further the two tubes forming the gap partly overlap the one the other.

The tube 6a is offset towards the end of the multicolor pencil. A spring 9a is fixed on this tube 6a, and the free end of spring 9a is tongue-shaped and projects with a curved nose 9b through a slot 8b in the spring 8a fixed on the tube 7a. The two blade springs are permanently in engagement with the corresponding serrated portion of the lead holder, as in the first form of 15 construction. A considerable portion of the tube 7a is guided in the tube 6a and its end bears against the spring 20. By a screw ring 22a on the end of tube 7a and screwed into the casing of the multicolor pencil to securely hold the 20 whole mechanism and by an abutment on the other end, the tube 7a is prevented from shifting on the grooved rod 18a. Owing to this arrangement a lead which is in the writing position is 25 securely held and cannot be pushed back even if its point is pressed strongly on to a paper. The grooved rod 18a has a bore 18b which does not extend from one end to the other. In this bore the spring 27 is located, against which the noses of the lead holders bear. In this form of construction the noses must evidently project inwards into the bore 18b. This bore 18b is closed at the open end by a rubber stopper 29 which serves as shock damper for the suddenly returning lead and prevents breaking of the same. 35

The manner of operation is similar to that of the multicolor pencil according to the first form of construction.

The invention is not limited to the forms of construction shown, as different alterations are 40 possible without departing from the scope of the invention.

I claim:

1. A multicolor pencil, comprising in combination with the casing having a removable point, a 45 press piece in the rear end of said casing, a resilient device in said casing consisting of a rear shiftable tube, a stationary front tube and a compression spring between the tube, means for transmitting the movement of said press piece 50 upon said shiftable tube, a grooved rod extending through said resilient device, lead holders one in each groove of said rod and projecting from the front end of the stationary part of said resilient device, means for transmitting the movement of the shiftable tube of said resilient device to the corresponding lead holder, means for moving forward said shiftable tubular part accompanied by compression of the said coil spring, a 55 spiral spring wound around the lead holders in 60 said grooved rod, the moving forward of any of said lead holders compressing said last mentioned spring.

2. A multicolor pencil as specified in claim 1, in which the resilient device is composed of a 65 shiftable tube having an upwardly directed projection near its rear end, and of a stationary front tube with a wide slot extending rearwards from its front end, two blade springs placed the one on the other, the upper blade spring having a 70 slot near its rear end and the lower blade spring having a slot at a short distance from its front end, a rivet fixing said lower blade spring on the shiftable tube and projecting through the slot in the upper blade spring, a rivet connecting the up- 75

per blade spring with the stationary tube and extending through the slit in said lower blade spring.

3. In a multicolor pencil as specified in claim 1, a grooved rod comprising a rear portion extending through the resilient device and of circular cross-section, a front portion also of circular cross-section, and a middle portion of square cross-section, a ring fixed on said middle portion of square cross-section and serving as abutment for the front end of the resilient device.

4. In a multicolor pencil as specified in claim 1, a ring fixed on the middle portion of the grooved rod, lead holders consisting of a wire and located one in each groove of the grooved rod, a sleeve-like holder fixed at the front end of each wire and projecting beyond the front end of the grooved rod, a serrated rear portion of said wire

adapted to be engaged by the curved front ends of the blade springs of the resilient device, and an upwardly projecting nose on the front end of said serrated portion and bearing against the ring on said grooved rod.

5. In a multicolor pencil as specified in claim 1 in combination with the lead holders in the grooved rod, having each a serrated portion and an upwardly projecting nose at the front end of this serrated portion, a collar on the front end of the grooved rod, a spiral spring wound around said grooved rod and bearing with one end against said collar and with the other end against the noses of the serrated portions of the lead holders to secure said lead holders in their operative position.

WILLY SCHMIEGLITZ.
